UNITED STATES PATENT OFFICE.

HERMANN HILL, OF SAVANNAH, GEORGIA, ASSIGNOR TO PRENDERGAST ELECTRIC TYPEWRITER COMPANY, A CORPORATION OF MAINE.

CARRIAGE MECHANISM FOR TYPE-WRITING MACHINES.

SPECIFICATION forming part of Letters Patent No. 732,555, dated June 30, 1903.

Application filed December 16, 1902. Serial No. 135,387. (No model.)

To all whom it may concern:

Be it known that I, HERMANN HILL, a subject of the Emperor of Austria-Hungary, residing in Savannah, county of Chatham, State 5 of Georgia, have invented certain new and useful Improvements in Carriage Mechanism for Type-Writing Machines, of which the following is a specification.

My invention relates to type-writing machines and more especially to carriage-feeding mechanism for such machines which shall be especially adapted for use in motor-operated machines of the character disclosed and claimed in the joint application of John S. 10 Harrison and myself, filed April 12, 1902, Serial No. 102,592, where a movable element of a motor, such as an electric motor, is controlled by the movements of the key-levers to actuate all the printing elements, including 15 the carriage; and my objects are to provide an improved carriage-feeding mechanism which shall be positive and reliable in operation, possessing the fewest number of parts and characterized by direct and positive motions, 20 and which shall be economical of manufacture and durable in use.

With these objects in view my invention consists of the novel construction and details thereof, as hereinafter described with reference to the accompanying drawings and more 25 particularly pointed out in the claims.

In the drawings, Figure 1 is a side elevation, partly sectional, of a carriage mechanism embodying my invention. Fig. 2 is a similar 30 view of the opposite side, showing the parts in the same position. Fig. 3 is a top plan view. Fig. 4 is a similar view showing a different position of the parts, and Fig. 5 is a detail showing the connection of the carriage- 35 operating lever with a movable element of the machine.

Referring now to the drawings, in which the same reference characters indicate the same or corresponding parts in all the views, 40 the operating-lever Y' is fulcrumed on the fixed frame at y⁴ and has one end detachably connected with the core or armature I of a solenoid or magnet by means of a swinging link i³.

50 The carriage Y is slidably mounted on transverse ways y, with its rack y' adapted to be

engaged by a pawl y², preferably with several teeth, which pawl is pivotally supported at y³ upon a plate Z, slidably mounted in suitable bearings z on the fixed frame. The 55 plate Z has an inclined slot z', in which works a roller z² on the end of the carriage-operating lever Y', fulcrumed at y⁴ on the frame, with its hooked end engaging one of the links i³ on the core I of the solenoid or other movable 60 element controlled by the keys. The lower end of the slot z' is vertical, so that when the roller z² reaches this point the plate Z is stopped, as in Fig. 4, the pawl y² being in engagement with the rack y', and to effect 65 upward movement of the pawl y² to engage said rack a pin y⁵ on the pawl engages a slot x⁶ in a cam X', fulcrumed at x⁷ on the plate Z, a pin x⁸ on said cam-plate X' being adapted to engage a cam-track z³ on the said lever Y', 70 whereby as the plate Z is moved backward by the roller z² the cam-plate X' is swung on its pivot, so that the slot x⁶ will raise the pin y⁵, and thereby the pawl y², into engagement with the rack y'. The lever Y' being now released by the motor, the spring y⁶ pushes the lever Y' up and causes the roller z² to pull the plate Z one notch or tooth, thus moving the carriage, during which movement the forward eccentrically-arranged edge x⁹ of the 80 cam-plate X' strikes a fixed stud z⁴, thereby swinging the plate X' upwardly on its pivot and pulling the pin y⁵ and the pawl y² downward to the released position of Figs. 1 and 2. To check the carriage at the proper point and 85 prevent it moving more than one space, a pivoted checking-pawl arm s, fulcrumed on a post s', has a roller s² normally pressed into contact with the rack y' by a spring s³, which pawl-arm is provided with a toe s⁴ adapted to 90 engage a projection s⁵ on a rock-shaft arm S', connected by a link s⁶ with the sliding plate. These parts are so arranged and timed that when the plate Z slides forward to feed the carriage the toe s⁴ is held down by the projection s⁵ an instant before the end of the feeding movement and so held while the rocker-arm is swinging the distance of the width of the projection, so that the momentum of the carriage is positively checked at 95 the proper instant to prevent the carriage from moving more than one space, because 100

at this instant the roller s^2 is positively held into contact with the rack y' , the roller s^3 normally answering the purpose during the other part of the movement of the carriage.

5 I claim as my invention—

1. In a type-writing machine having operating-keys, the combination with a movable element controlled by the keys, of a carriage, a feed-pawl slidably mounted on the fixed

10 structure, connections between the movable element and said pawl, a checking-pawl adapted to check the momentum of the carriage, and locking devices operated by the movement of the feed-pawl to lock said check-

15 ing-pawl positively into engagement with the carriage as the same completes its required movement for spacing, substantially as described.

2. In a type-writing machine having operating-keys, the combination with a carriage, a movable carriage-operating lever, a movable element for operating the same, a sliding plate operated by said lever and having a feed-pawl pivotally mounted thereon, and

25 devices on the pawl and plate arranged to swing the pawl into engagement with the carriage for forward feed of said carriage as the plate is moved forwardly by the lever, and a device for swinging said pawl to release the

30 same from engagement with the carriage when the spacing movement is completed, substantially as described.

3. In a type-writing machine, the combination with a carriage, of a pivoted feed-pawl

35 slidably carried upon the frame of the machine, an operating-lever adapted to impart a backward motion to the pawl, connections between the lever and pawl for imparting an upward motion thereto for engagement with

40 the carriage, and a forward and downward motion thereto when the lever moves in the opposite direction, substantially as described.

4. In a type-writing machine, the combination with a carriage, of a plate slidably mounted

45 on the frame of the machine, a feed-pawl pivotally supported thereon, an operating-lever having an arm engaging said plate, movement of the lever in one direction causing backward motion of the plate and, in the

50 other direction, forward movement of the same, and connections between the lever and the pawl adapted to cause upward movement of the pawl as the plate is moved backward by the lever and downward movement of said

55 pawl when the forward movement of the plate and the pawl is completed, substantially as described.

5. In a type-writing machine, the combination with a carriage, of a plate slidably mounted

60 on the frame of the machine, a feed-pawl pivotally supported thereon, an inclined slot in said plate, an operating-lever having one arm engaging said slot so that downward movement of said arm will impart backward

65 motion to the plate and upward movement thereof, forward motion to the same, and connections between the said lever-arm and the

pawl adapted to cause the pawl to move into engagement with the carriage when the plate moves backward and out of engagement therewith when the pawl has completed its forward feeding motion, substantially as described.

6. In a type-writing machine, the combination with a carriage, of a plate slidably mounted on the frame of the machine, of a feed-pawl pivotally supported thereon, an inclined slot in said plate, an operating-lever having an arm engaging said slot, a cam having a slot

75 therein pivotally supported on the sliding plate, a pin on the pawl engaging said slot, a connection between the arm of the lever and the cam adapted to rock the cam on its pivot when the arm moves the sliding plate backward, thereby swinging the pawl into engagement with the carriage, and means for swinging

80 said cam in the opposite direction to draw the pawl out of engagement with the carriage when the lever-arm has moved the sliding plate in the opposite direction, substantially as described.

7. In a type-writing machine, the combination with a carriage, of a plate slidably mounted on the frame of the machine, of a feed-pawl pivotally supported thereon, an inclined slot in said plate, an operating-lever having an arm engaging said slot, a cam having a slot

85 therein pivotally supported on the sliding plate, a pin on the pawl engaging said slot, a connection between the arm of the lever and the cam adapted to rock the cam on its pivot when the arm moves the sliding plate backward, thereby swinging the pawl into engagement with the carriage, and means for swinging

90 said cam in the opposite direction to draw the pawl out of engagement with the carriage when the lever-arm has moved the sliding plate in the opposite direction, substantially as described.

7. In a type-writing machine, the combination with a carriage, of a plate slidably mounted on the frame of the machine, of a feed-pawl pivotally supported thereon, an inclined slot in said plate, an operating-lever having an arm engaging said slot, a cam having a slot

95 therein pivotally supported on the sliding plate, a pin on the pawl engaging said slot, a connection between the arm of the lever and the cam adapted to rock the cam on its pivot when the arm moves the sliding plate backward, thereby swinging the pawl into engagement with the carriage, and a lug on the frame

100 adapted to engage the cam as the plate completes its feeding motion and swing the said cam so as to draw the pawl out of engagement with the carriage, substantially as described.

8. In a type-writing machine, the combination with a carriage, of a feed-pawl slidably carried on the frame of the machine, means for imparting backward and upward motion

110 to the pawl to cause it to engage the carriage and forward and downward motion to cause it to move the carriage and disengage therefrom, a checking-pawl normally in contact

115 with the carriage, and connections between the feed-pawl and the checking-pawl adapted to positively lock the said checking-pawl against the carriage about the time the spacing movement of the carriage is completed,

120 substantially as described.

9. In a type-writing machine, the combination with a carriage, of a plate slidably mounted on the frame of the machine, a feed-pawl pivotally supported thereon, means for moving the plate and causing the pawl to engage

125 and disengage the carriage to move the latter for spacing, a checking-pawl normally in yielding contact with the carriage, and connections between said checking-pawl and sliding plate

130 so timed in action as to positively lock the checking-pawl against the carriage to check its momentum when the spacing movement is completed, substantially as described.

10. In a type-writing machine, the combination with a carriage, a plate slidably mounted on the frame of the machine, a feed-pawl pivotally supported thereon, means for moving the plate to cause the pawl to engage and disengage the carriage for spacing, a checking-pawl normally held in yielding contact with the carriage, a rock-shaft arm having a lug thereon, a link connecting said plate with the rock-shaft arm, and a lug on the checking-pawl adapted to be engaged by the lug on the rock-shaft arm, as the spacing movement is completed, whereby the momentum of the carriage will be checked when the feed-pawl is released from engagement therewith, substantially as described. **15**

In testimony whereof I have signed my name to this specification in the presence of two subscribing witnesses.

HERMANN HILL.
